UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

AIR-FEED-CONTROLLING DEVICE.

Application filed June 20, 1925. Serial No. 38,443.

This invention relates to fluid actuated rock drills, and more particularly to a feed controlling device for the feeding element of rock drills of the stoper type.

5 An object of this invention is to enable the feeding element of a stoper type rock drill to be controlled in a simple and improved manner.

10 Another object is to insure perfect seating of the valve which controls the release of pressure fluid from the air feeding element and a further object is to improve generally in feed controlling devices for rock drills in order to insure ease and simplicity of operation and certainty of functioning.

15 Other objects will be in part obvious and in part pointed out hereinafter.

The invention consists of the combinations of elements, features of construction and arrangement of parts having the general mode of operation substantially as hereinafter described and more particularly pointed out in the appended claims and illustrated in the accompanying drawings, in 25 which—

Figure 1 is a view in elevation partly broken away of a stoper type rock drill showing the relation of the feed controlling mechanism with the feeding element.

30 Figure 2 is an enlarged detail view in elevation and partly in section showing a feed controlling mechanism constructed in accordance with the practice of the invention, and in which the valve is closed.

35 Figure 3 is a view similar to Figure 2 showing the cooperation of the parts for opening the valve, and

40 Figure 4 is a transverse view in section taken through Figure 2 on the line 4—4 looking in the direction of the arrows.

45 Referring to the drawing, the invention is shown embodied in a rock drill of the stoper type having a cylinder A and a back head B. A front head C is supported by the cylinder at its front end and is secured thereto by means of spring pressed side bolts D. Disposed within the front head C is a drill steel E and a motor (not shown) operative in a motor casing F imparts rotary motion to the drill steel E to keep said steel 50 free within the drill hole.

In order to move the drill forwardly as the drill steel E penetrates the work, a feeding element is provided. In this instance,

the feeding element comprises a feeding cylinder G, and a piston H arranged to reciprocate within the cylinder G carries a piston rod J to which is secured at its outer end a rock engaging pointer K. In this instance, the cylinder A, the motor casing F, the back 60 head B and the feeding cylinder G are held in operative relation with respect to each other by means of bolts L arranged on opposite sides of the drill.

Pressure fluid for actuating the percussive and feeding elements is supplied to the drill through a suitable connection O secured to the back head B. The admission of pressure fluid to the cylinders and to the gear motor is controlled by a suitable 70 throttle valve (not shown) having a throttle lever P.

In order to prevent rotation of the drill with the drill steel, a rotation handle Q is secured to the back head B and held against 75 removal therefrom by a nut R. A passage S is formed through the handle Q and is in communication with the feeding cylinder G through a passage T formed in the back head.

80 Suitable means are provided for regulating the maximum exhaust from the pressure feeding cylinder for immediate pressure values, and to this end, a plug U is secured in a recess V at the end of the rotation handle 85 Q and has a restricted passage W. A needle valve X screwed into the end of the recess V controls the size of the outlet opening of the passage W and is preferably provided with a nut Y for locking the valve 90 in position.

In accordance with the present invention, an extension Z, which is in this instance formed integrally with the rotation handle Q, is arranged at an angle with respect to 95 said rotation handle and is provided with a passage b communicating at its inner end with the recess V. The free end of the extension Z is in this instance screw threaded at at c to receive a suitable nut d. A lock 100 washer e is interposed between the nut and a shoulder f for preventing accidental removal of the nut. The outlet opening of the passage b is preferably countersunk concentrically with said passage to provide a 105 seat g for a needle valve h which controls the exhaust of pressure fluid through the rotation handle from the feed cylinder.

- Arranged slidably on the extension Z is a sleeve k having a plurality of inwardly extending ribs o to cooperate with grooves p formed on the extension Z to prevent rotation of the sleeve with respect to said extension, but permitting longitudinal movement of said sleeve. The outer end of the sleeve k is in this instance screw threaded as at q to receive a sleeve nut r. An enlarged bore s is formed at the outer end of the sleeve k to receive a spring t interposed between the nut d and a shoulder u of the sleeve for holding the sleeve in a normally upward position.
- 15 The sleeve nut r is in this instance provided with a bore v to receive slidably a flange w formed integrally with the valve h. The flange w is preferably of somewhat larger diameter than the bore s to enable a shoulder x of the sleeve k to engage said flange for opening the valve h. The face of the flange w and the shoulder x are so positioned that a considerable space y exists therebetween when the sleeve k and the valve h are in their normal resting positions. Holes z and 2 are formed in the valve h and the sleeve nut r respectively to provide a path for pressure fluid exhausted from the feeding element to atmosphere. In order to hold the valve h yieldingly upon its seat g, a spring 3 is interposed between the end wall of the sleeve nut r and the said valve, and is preferably held central with respect to the valve by means of a projection 4 formed coaxially with the valve.
- 20 In the operation of the device, whenever the drill steel encounters a soft spot in the material being drilled, it may be desirable to reduce the pressure in the air feeding element somewhat. This may be accomplished by moving the sleeve k downwardly on the extension Z until the shoulder x bears against the flange w of the valve h. Continued downward movement of the sleeve will unseat the valve, and a portion of the pressure fluid from the air feeding cylinder H is exhausted through the rotation handle to atmosphere through the ports z and 2 in the valve h and the sleeve nut r respectively.
- 25 In this manner the drill may be fed slowly into the work, or, if desired, the drill may be withdrawn somewhat from the work by opening the valve h to wide limits and per-

mit a free flow of pressure fluid from the feeding cylinder to atmosphere.

55 The advantages of the invention reside in the fact that a sensitive control of the feeding element may be obtained, and due to the clearance provided between the shoulder x of the sleeve k and the flange d of the valve, 60 the valve will not become accidentally unseated during the normal operation of the machine.

I claim:

1. In a feed controlling device for rock 65 drills, the combination of a percussive cylinder and an air feeding element, a back head for the cylinder, a rotation handle secured to the back head and having a passage therethrough, a valve seat formed at one end of 70 said passage, a valve to normally rest on said seat, a sleeve slidable on the handle for opening the valve, said sleeve being normally out of contact with the valve, and a spring for closing said valve.

75 2. In a feed controlling device for rock drills, the combination of a percussive cylinder and an air feeding element, a back head for the cylinder, a rotation handle secured to the back head and having a passage therethrough, a valve seat at the outlet end of 80 said passage, a needle valve to normally rest on said seat, a sleeve slidable on the handle for guiding and opening the valve, a spring for closing the valve, and a spring cooperating with the sleeve and the handle for moving the sleeve in one direction.

85 3. In a feed controlling device for rock drills, the combination of a percussive cylinder and an air feeding element, a back head 90 for the cylinder, a rotation handle secured to the back head and having a passage therethrough communicating at one end with the said cylinder, a valve seat at the outlet opening of the passage, a needle valve 95 normally resting on said seat, a sleeve slidably on the handle for centralizing and opening the valve, a spring for holding the sleeve in a normally upward position, a spring between the valve and the end of the sleeve to 100 hold the valve normally closed, and cooperating ribs on the handle and the sleeve for preventing rotation of the sleeve.

In testimony whereof I have signed this specification.

CHARLES C. HANSEN.
